UNITED STATES PATENT OFFICE.

ELMER L. KNAB, OF ROCHESTER, NEW YORK, ASSIGNOR, BY DIRECT AND MESNE ASSIGNMENTS, TO THE KNAB CORPORATION, OF ROCHESTER, NEW YORK, A CORPORATION OF NEW YORK.

EAVES-TROUGH HANGER.

Application filed March 20, 1925. Serial No. 16,975.

To all whom it may concern:

Be it known that I, ELMER L. KNAB, a citizen of the United States, residing at Rochester, in the county of Monroe and State of New York, have invented certain new and useful Improvements in Eaves-Trough Hangers, of which the following is a specification.

The object of this invention is to provide a new and improved type of hanger for supporting eaves troughs.

This and other objects of this invention will be fully illustrated in the drawing, described in the specification and pointed out in the claims at the end thereof.

In the accompanying:

Figure 1 is a perspective view of the eaves trough hanger with an eaves trough or gutter shown supported therein.

Figure 2 is a vertical sectional view of the eaves trough hanger.

Figure 3 is a detail perspective view of one form of the supporting bracket for the eaves trough hanger.

Figure 4 is a front elevation of another form of the supporting bracket for the eaves trough hanger.

Figure 5 is a horizontal sectional view of the eaves trough hanger and its supporting bracket, the section being taken on the line 5^x-5^x of Figure 1.

Figure 6 is a vertical cross section of the eaves trough hanger, the section being taken on the line 6^x-6^x of Figure 1.

Figures 7 and 8 are sectional views of a modified form of the construction of the hanger.

In the several figures of the drawing like reference numerals indicate like parts.

Eaves troughs or gutters must be supported on the edge of roofs so as to catch the water running off or dripping therefrom and conduct this water to a predetermined point in the eaves trough or gutter from whence a conductor pipe carries the water off into the sewer. In supporting the eaves trough or gutter it is, therefore, of utmost importance that the eaves trough or gutter be held suspended so that it quickly drains

all of the water that runs into it from the roof. The supports or hangers for the eaves trough or gutters must, therefore, be attached to the house to support the eaves trough at the proper angle or pitch.

In order to facilitate this in the most convenient manner the eaves trough hanger forming the subject matter of my present invention is provided with an adjustment that makes it possible to raise or lower the eaves trough or gutter at any point until it is supported at the desired angle throughout its full length. The eaves trough hanger is also constructed so that this adjustment may be made quickly after the eaves trough has been placed into the hanger.

As illustrated in the figures of the drawing the hanger comprises a vertical bracket 1 formed up of sheet metal. The sides of this bracket are bent up to form two angular runways 2 and 3 one on each side of the bracket. The upper end of the bracket is left flat and is provided with a series of holes 4, 4 thru which nails can be driven to fasten the bracket in place on the side of a house. The middle of the bracket has an elongated blister or rib 5 struck up thereon in order to increase the rigidity thereof. In the elongated blister are provided horizontal ridges 6 or suitable round depressions 7 or in fact any serrations in one form or another for a purpose that will presently appear.

The two angular runways formed on each side of the bracket form a dovetailed groove in which the hanger 8 proper is clamped in place. This hanger is bent up of sheet metal in the form of an inverted channel having a semi-circular outline, except for a short length at the end thereof which is left straight. This straight section of the hanger has its flanges spread angularly so as to be parallel to the angular flanges of the bracket between which they are clamped in place. The short straight section of the hanger proper is adapted to telescope into the dovetailed groove of the bracket. A set screw 9 is threaded into the straight section of the hanger from the front thereof so that its end engages into the ridges or depressions in the bracket 1. When drawn tight the set screw forces the angular flanges of the hanger against the angular flanges of the bracket while at the same time engaging into the ridges or depression in the bracket 1. In this way the hanger can be locked securely in place in the bracket at any desired elevation thereon.

The free end of the hanger has the flanges cut away on the side forming a flat extension 10 thereon that is bent outwardly and upwardly of the hanger. This provides a ledge on which the cylindrical bead of the eaves trough to be suspended by the hanger is adapted to rest. The eaves trough or gutter is placed into the hanger with the inner and thin edge placed under the head of the set screw 9 and the outer and beaded edge located on the ledge formed on the outside of the hanger. The flat extension is then bent over the beaded edge of the eaves trough or gutter to hold the gutter or eaves trough in place in the hanger so that it cannot disengage itself from it.

In placing the eaves trough hanger on a building the upper end of the bracket is first fastened thereto by driving nails thru the three holes 4, 4 in the upper end thereof and the one hole 12 provided near the lower end of the bracket. When the bracket is to be fastened to the side the form illustrated in Figure 4 is used and when the bracket is to be anchored underneath the shingles of the roof the form illustrated in Figure 3 is used. The latter form has its flat end bent back at an angle of 45 degrees so as to conform as closely as possible to the pitch of the roof to which it is to be anchored. After the brackets are in place the hangers are temporarily attached thereto by sliding the vertical straight inner end of the hanger into the dovetailed groove of the hanger and then threading the set screw of the hanger against the bracket and into one of the ridges of depressions. The manner in which the flanges forming the angular runways are bent up on the bracket provides angular guides at the top of these guide ways so that when the straight section of the hanger is to be attached to the hanger it can be readily slipped into the dovetailed groove from the top as the angular ends of the angular runways forming the dovetailed groove will guide the flanges of the straight section of the hanger in place in the dovetailed slot.

After the hanger is in place on the bracket and the eaves trough and gutter is placed into the hanger, the hanger may be raised or lowered with the eaves trough until the eaves trough is placed at the proper angle or pitch along the edge of the roof. This is done by simply releasing the set screw 9 until its end has been disengaged from the ridges or depressions in the bracket after which the hanger can be moved up or down in the dovetailed groove in the bracket and again be clamped therein after the desired elevation has been reached.

The cross section of the hanger as illustrated in Figures 1, 2 and 6 is that of an inverted channel having vertical sides.

This may be changed to the cross section illustrated in Figure 7 by bending the sides of the channel inwardly to reduce the thickness of the hanger.

In Figure 8, I have illustrated another cross section of the hanger in which the flanges thereof are brought together without a space between them and instead of an inverted channel the bracket consists of two parallel flanges placed side by side.

I claim:

1. In an eaves trough hanger, the combination of a bracket having a dovetailed groove at the front thereof, a stiffening rib in the bottom of said groove, depressions in said stiffening rib, a hanger having a straight section with tapering sides adapted to slide in the dovetailed groove in said bracket, a set screw threaded into said hanger and adapted to engage the depressions in said stiffening rib in said bracket and force the tapered sides of said hanger from the inside against the inner side of the dovetailed grooves in said bracket.

2. In an eaves trough hanger, the combination of a bracket having a dovetailed groove at the front thereof, a stiffening rib in the bottom of said groove, depressions in said stiffening rib, a hanger having a straight section with tapering sides adapted to slide in the dovetailed groove in said bracket, a set screw threaded into said hanger and adapted to engage the depressions in said stiffening rib in said bracket and force the tapered sides of said hanger from the inside against the inner side of the dovetailed grooves in said bracket, said set screw having a head, a ledge formed on the outer end of said bracket, a flexible extension projecting from the outside of said ledge, the eaves trough to be supported in said hanger being adapted to engage under the head of said set screw with one side thereof, and rest on said ledge on the outer end of said bracket with the outer edge, said flexible extension being adapted to lock the side of the eaves trough supported in said ledge in place thereon.

3. In an eaves trough hanger, the combination of a bracket formed of sheet of metal angular flanges bent up on the sides of the bracket forming a dovetailed groove in the front of said bracket, an elongated blister struck up centrally of said groove the full length thereof, depressions on top of said blister, a semi-circular hanger bent up of an inverted U shaped channel, a straight section extending from said semi-circular hanger, angular sides on said straight section of said hanger, said straight section with its angular sides being adapted to telescope in said dovetailed groove of said bracket, a set screw threaded into said hanger and adapted to engage into

the depressions in said blister and force the angular sides of said hanger from the inside against the angular sides of said dovetailed groove in said bracket, a flat extension on the outer end of said semi-circular hanger, said flat extension being bent outwardly and upwardly to form a ledge.

on the end of said hanger and allow the outer end of said extension to lock the edge of the eaves trough in place on said ledge.

In testimony whereof I affix my signature.

ELMER L. KNAB.
